GALLEY FOR AIRCRAFT

Anthony J. Fiori, Seac Cliff, Edward J. Dziedziula, North Massapequa, and Ralph R. Pecoraro, West Islip, N.Y., assignors to Ref Manufacturing Corporation, Mineola, N.Y., a corporation of New York

Application January 8, 1959, Serial No. 54,076

Term of patent 14 years

(Cl. D81—10)

FIG. 1

The single figure of the drawing is a perspective front and side view of a galley for aircraft. The other side, top and back, not shown, are substantially plain.

We claim:

The ornamental design for a galley for aircraft, substantially as shown and described.
